CLAIM

The ornamental design for the table, as shown and described.

DESCRIPTION

FIG. 1 is an isometric view of a first embodiment of the table of the present design;

FIG. 2 is a front elevation view thereof, the rear elevation view being identical thereto;

FIG. 3 is a right side elevation view thereof, the left side elevation view being identical thereto;

FIG. 4 is a top plan view thereof;

FIG. 5 is an isometric view of a second embodiment;

FIG. 6 is a front elevation view of the second embodiment, the rear, right side and left side elevational views being identical thereto; and,

FIG. 7 is a top plan view of the second embodiment.

The broken lines in the figures are for illustrative purposes only and form no part of the claimed invention.
